TOY PROJECTOR

Carlos Fernandez, Tijuana, Mexico

Application July 19, 1941, Serial No. 403,218

4 Claims. (Cl. 88—24)

This invention relates to picture projectors and more particularly to a toy projector.

An object of this invention is to provide a projector which is adapted to project pictures from an elongated strip of paper or the like so that the apparatus or machine may be operated by a child.

Another object of this invention is to provide a projector of this kind which includes one or more light bulbs mounted in a housing and a mirror positioned in the housing for reflecting an image forwardly through an adjustable lens structure.

A further object of this invention is to provide a projector of this kind which is simple in construction so that it will withstand relatively hard usage and will not readily get out of order when handled by a child.

A further object of this invention is to provide a projector of this type which may be used as a sort of amusement for children, being capable of projecting pictures such as appear in the comic sections of newspapers or the like, and which does not require that the pictures be transparent.

To the foregoing objects and to others which may hereinafter appear, the invention consists of the novel construction, combination and arrangement of parts as will be more specifically described and illustrated in the accompanying drawings, wherein is shown an embodiment of the invention, but it is to be understood that changes, variations and modifications may be resorted to which fall within the scope of the invention as claimed.

In the drawings:

Figure 1 is a perspective view of a projector constructed according to an embodiment of this invention.

Figure 2 is a sectional view taken on the line 2—2 of Figure 1.

Figure 3 is a sectional view taken on the line 3—3 of Figure 1.

Figure 4 is a sectional view taken on the line 4—4 of Figure 3.

Figure 5 is a sectional view of the combined closure and strip holding member taken substantially on the line 5—5 of Figure 3, and

Figure 6 is a fragmentary sectional view of the top of the projector showing the use of a frosted glass for receiving an image to be projected.

Referring to the drawings the numeral 10 designates generally a housing which is adapted to be constructed out of metal. The housing 10 includes a top wall 11, a rear wall 12, opposite end walls 13 and 14 and a front wall 15. The 55

front wall 15 is formed of a pair of rearwardly divergent wall members 16 and 17 which are connected together at their convergent ends by means of an intermediate wall member 18 disposed in parallel relation with respect to the rear wall 12.

The top wall 11 is formed with a window or opening 19 which is rectangular in configuration and the opposite end portions of the window 19 are provided with downturned strip guide members 20 as shown in Figure 3. A U-shaped reel support 21 is mounted on the top wall 11 adjacent the end wall 13 and has the bight 22 thereof secured as by spot welding or the like to the upper surface of the top wall. The details of construction of the reel support 21 are shown more in detail in Figure 4, and are similar in every respect to a second reel support 23 which is secured to the top wall 11 adjacent the end wall 14.

The reel supports 21 and 23 each include an inwardly projecting pin or trunnion 24 which is secured to a vertical leg 25 of the U-shaped support, the support 25 being formed with an opening 26 through which stud 27 is adapted to engage. The stud 27 may be upset at its outer ends so as to tightly hold the pin 24 in the opening 26. The pin 24 may be formed with an annular flange 28 abutting against the inner face of the vertical leg 25. Each U-shaped reel support is also provided with a stub shaft 29 which is journaled through an opening 30 formed in the opposite vertical leg 31. A cylindrical housing 32 is fixed by welding or the like to the outer side of the vertical leg 31 and engages loosely about the stub shaft 29. The stub shaft 29 is formed with a reduced diameter outer portion 33 which is adapted to be secured to a bell crank or handle 34. An outer end wall 35 is carried by the cylindrical housing 32 and the reduced portion 33 of the shaft 29 rotatably engages through the outer end wall 35. A spring 36 engages about the reduced shaft portion 33 and one end of the spring 36 bears against a shoulder 37 formed at the junction between the reduced shaft member 33 and the stub shaft 29.

The other or outer end of the spring 36 abuts against the inner side of the end wall 35. In this manner the stub shaft 29 is constantly urged inwardly of the vertical leg 31. The inner end portion of the shaft 29 is formed with a flat end member 38 which is engageable in a rectangular opening 39 formed in one end 40 of a reel 41. The other end 42 of the reel 41 is formed with a round opening 43 within which the supporting

pin 24 is adapted to engage. The cylindrical body 44 of the reel 41 is formed hollow and provided with an elongated slot 45 through which one end portion of a picture strip is adapted to engage so that the balance of the strip may be wound about the body 44.

The picture strip S which is adapted to be wound on the two reels is adapted to movably engage beneath a hinged closure 46. The closure 46 is formed from a flat plate 47 having a hinged barrel 48 at one edge through which a pintle 49 engages. The opposite ends of the pintle 49 are bent downwardly as at 50 and riveted or otherwise fixed secured to the top wall 11 forwardly of the forward edge of the window or opening 19. The opposite or rear edge of the plate or closure 46 is provided with a downturned flange 51 which is adapted to rest on the upper side of the top wall 11 so as to prevent any light from the interior of the housing 10 from leaking out towards the rear thereof.

The closure 46 is provided adjacent the opposite ends thereof with a pair of rollers 52 and 53. The roller 52 is mounted on a stationary shaft 54 which is formed with upturned opposite end portions 55 which are secured as by riveting or the like as indicated at 56 to the plate 47. The roller 53 is similar in every detail to the roller 52 and is mounted on the plate 47 in the same manner as the roller 52. The closure 46 is provided with a pivoted latching member 57 adjacent the rear or free edge thereof which is formed with a latch element 58 engageable beneath the top wall 11 adjacent the rear edge of the window 19.

A mirror 59 is disposed within the housing 10 being mounted on a horizontally disposed bracket or plate 60 which is formed with a depending flange 61 secured as by welding or the like to the inner side of the rear wall 12. The opposite ends 40 of the supporting plate 60 are upturned as at 62 so as to hold the mirror or reflector 59 against endwise movement. The forward edge of the supporting member 60 is also upturned on an obtuse angle as at 63 and the lower edge of the 45 mirror 59 seats on the upper side of the flange 63 as shown in Figure 2. The mirror 59 is disposed on substantially a forty-five degree angle with respect to the top wall 11 so that the image reflected by the mirror 59 from the image strip S will be reflected horizontally and outwardly through the front wall 15. Preferably, the mirror supporting member 60 is braced by means of an angled bracing member 64 which is formed with an obtusely disposed upper forward portion 65 which may be welded or otherwise fixed to the underside of the supporting member 60. The opposite or lower end of the brace 64 is bent obtusely as at 66 and welded, soldered or otherwise fixed to the inner side of the rear wall 12.

The bracing member 64 as shown in Figure 3 is formed with a longitudinal bead 67 so as to reinforce this strip and prevent longitudinal bending thereof. A baffle or deflector 68 is mounted within the housing 10 in downwardly spaced parallel relation with respect to the top wall 12 and is formed with an upturned forward end portion 69 which may be welded or otherwise fixed to the inner side of the front wall section 18. The rear end of the deflector 68 terminates substantially in a vertical plane coplanar with the forward edge of the reflector 59. The interior of the housing 10 is preferably lined with a heat resistant lining 70 in the form of asbestos or the like, so that the exterior of the housing

will not become unduly heated from the light bulb or bulbs mounted interiorly thereof.

A bottom wall 71 is disposed in the housing 10 and is formed with upturned opposite end portions or flanges 12 which are adapted to be secured as by fastening devices 73 to the opposite end walls 13 and 14. The bottom wall 71 is removable from the housing 10 and has mounted thereon a pair of light sockets 74 and 75 for receiving light bulbs 76 and 77 respectively. The socket 74 is formed with a base 78 secured by fastening members 79 to the upper side of the bottom wall 71 and the socket 75 is formed with a base 80 secured by fastening members 81 to the upper side of the bottom wall 71. The two light bulbs 76 and 77 are disposed in the space between the opposite end portions of the reflector 59 and the opposite end walls 13 and 14 so that the light from the bulbs 76 and 77 will be reflected from the reflecting member 59.

The end wall 13 is provided adjacent the upper portion of the light bulb 76 with an opening 82 and a downwardly opening housing 83 is secured to the outer side of the side wall 13 and encompasses the opening 82. The housing 83 is substantially U-shaped in transverse section and is formed with a top wall 84 so as to prevent any light rays from passing upwardly from the opening 82. The lower end of the housing 83 terminates at a point spaced downwardly from the lower edge of the opening 82 so that the light rays which strike the outer wall 85 of the housing 83 will not be reflected downwardly. Preferably, the inner surface of the housing 83 is coated with an opaque coating so as to prevent the reflection of the light rays.

The opposite end wall 14 is also formed with an opening 86 and a substantially U-shaped housing 87 is secured as by welding or the like to the outer side of the end wall 14. The housing 87 includes a top wall 88 similar to the top wall 84 and the housing 87 is substantially of greater height or length than the opening 86 so that the lower edge thereof will be disposed in downwardly spaced relation to the lower edge of the opening 86. The interior of the housing 87 is also coated with an opaque coating to prevent the reflection of light rays.

The front wall member 18 is provided with an opening 89 through which the light rays and the projected image are adapted to pass. A U-shaped lens support 90 has the vertical legs 91 thereof secured to the front wall member 18 and a cylindrical lens barrel 92 is fixed to the front wall or bight 93 of the U-shaped support 91. A second lens barrel 94 is adapted to telescope into the stationary lens barrel 92 and is provided adjacent the outer end portion thereof with a lens 95. The image which is projected from the reflector 59 may be focused on a screen by moving the movable lens barrel 94 relative to the stationary barrel 92.

In the use and operation of this projector, the picture bearing strip S is adapted to be wound on one of the reels carried by a reel support and the end of the strip S is slipped into the elongated slot 45 of the opposite reel. The strip guiding member or closure 46 is initially disposed in a raised position so that the strip may be extended from one reel to the other in a position overlying the window 19. The strip guiding and holding member 46 may then be lowered to the position shown in Figure 1.

The light bulbs 76 and 77 are connected to a suitable source of electric current supply and

the lens 95 may then be focused on the screen so that the image reflected by the reflecting member 59 will be clear. The reel bearing the free end of the strip S is then turned by the crank 34 pulling the strip S across the window 19.

This projector is designed to project images, such as pictures, cartoons or the like, which may be in colors and mounted on an elongated strip for winding on the two reels 31. If desired, a frosted glass plate 96 may be disposed on the top wall 11 overlying the window 19 and any pictures or images may be drawn on the rough surface of the glass 96 and such images or pictures will be projected by the reflector 59 through the lens 95. In this manner the projector hereinafter described may be used either for projecting pictures on a flexible strip, such as paper or the like, or may be used to project pictures or drawings which a child may make on the frosted glass plate 96.

What I claim is:

1. A toy projector comprising a housing formed of front, rear, end, top and bottom walls, said top wall having a window therein, a pair of upstanding U-shaped reel supports fixed to said top wall adjacent the opposite ends of said window, a stationary pin carried by one leg of each support, a spring-pressed shaft aligning with said pin and carried by the other leg of each support, a crank fixed to said shaft, a plate engageable over said window, means hingedly mounting said plate on said top wall, a pair of spaced parallel image strip guide rollers beneath said plate, means rotatably mounting said rollers on said plate, a mirror in said housing below said window, means supporting said window at an angle whereby to reflect the image horizontally and forwardly, said housing having an opening in the front wall thereof through which the image is adapted to be projected, a lens support fixed to said front wall, a stationary lens barrel fixed to said support in alignment with said opening, an adjustable lens barrel telescoping said stationary barrel, a lens in said adjustable lens barrel, a pair of light sockets fixed to said bottom wall, and a light bulb in each socket and disposed in a position to project light rays onto the image exposed through said window and to project light rays onto said mirror.

2. A toy projector comprising a housing formed of front, rear, end, top and bottom walls, said top wall having a window therein, a pair of upstanding U-shaped reel supports fixed to said top wall adjacent the opposite ends of said window, a stationary pin carried by one leg of each support, a spring-pressed shaft aligning with said pin and carried by the other leg of each support, a crank fixed to said shaft, a plate engageable over said window, means hingedly mounting said plate on said top wall, a pair of spaced parallel image strip guide rollers beneath said plate, means rotatably mounting said rollers on said plate, a mirror in said housing below said window, means supporting said window at an angle whereby to reflect the image horizontally and forwardly, said housing having an opening in the front wall thereof through which the image is adapted to be projected, a lens support fixed to said front wall, a stationary lens barrel fixed to said support in alignment with said opening, an adjustable lens

barrel telescoping said stationary barrel, a lens in said adjustable lens barrel, a pair of light sockets fixed to said bottom wall, a light bulb in each socket and disposed in a position to project light rays onto the image exposed through said window and to project light rays onto said mirror, each end wall having an air vent opening therein, and a downwardly opening housing encompassing each air vent.

3. A toy projector comprising a housing formed of front, rear, end, top and bottom walls, said top wall having a window therein, a pair of upstanding U-shaped reel supports fixed to said top wall adjacent the opposite ends of said window, a stationary pin carried by one leg of each support, a spring-pressed shaft aligning with said pin and carried by the other leg of each support, a crank fixed to said shaft, a plate engageable over said window, means hingedly mounting said plate on said top wall, a pair of spaced parallel image strip guide rollers beneath said plate, means rotatably mounting said rollers on said plate, a mirror in said housing below said window, means supporting said window at an angle whereby to reflect the image horizontally and forwardly, said housing having an opening in the front wall thereof through which the image is adapted to be projected, a lens support fixed to said front wall, a stationary lens barrel fixed to said support in alignment with said opening, an adjustable lens barrel telescoping said stationary barrel, a lens in said adjustable lens barrel, a pair of light sockets fixed to said bottom wall, a light bulb in each socket and disposed in a position to project light rays onto the image exposed through said window and to project light rays onto said mirror, each end wall having an air vent opening therein, and a downwardly opening housing encompassing each air vent.

4. A toy projector comprising a housing formed of front, rear, end, top and bottom walls, said top wall having a window therein, a pair of upstanding U-shaped reel supports fixed to said top wall adjacent the opposite ends of said window, a stationary pin carried by one leg of each support, a spring-pressed shaft aligning with said pin and carried by the other leg of each support, a crank fixed to said shaft, a plate engageable over said window, means hingedly mounting said plate on said top wall, a pair of spaced parallel image strip guide rollers beneath said plate, means rotatably mounting said rollers on said plate, a mirror in said housing below said window, means supporting said window at an angle whereby to reflect the image horizontally and forwardly, said housing having an opening in the front wall thereof through which the image is adapted to be projected, a lens support fixed to said front wall, a lens means supported by said lens support and adapted to project the image, a pair of light sockets fixed to said bottom wall, and a light bulb in each socket and disposed in a position to project light rays onto the image exposed through said window and to project light rays onto said mirror.
